UNITED STATES PATENT OFFICE.

FREDOLIEN J. OBERER, OF PORTLAND, OREGON, ASSIGNOR, BY DIRECT AND MESNE ASSIGNMENTS, TO IRONCLAD SILO COMPANY, OF PORTLAND, OREGON, A CORPORATION OF OREGON.

COMBINED DOOR HINGE AND FASTENING.

1,172,550.

Specification of Letters Patent.

Patented Feb. 22, 1916.

Application filed January 16, 1914. Serial No. 812,605.

To all whom it may concern:

Be it known that I, FREDOLIEN J. OBERER, a citizen of the United States, and a resident of the city of Portland, county of Multnomah, State of Oregon, have invented a new and useful Improvement in Combined Door Hinges and Fastenings, of which the following is a specification.

My invention relates to the hinging and fastening of a door, or closure, which is so located as to be hard to operate; and my invention has for its general purpose the providing of hinging and fastening means conveniently and easily operated and so arranged as to be operable by one hand.

It is also the purpose of my invention to so construct my fastening means for the door that they will operate to lock the latter at its four corners, and by so doing hold it more securely than if fastened as usual.

An incidental object of my invention is to provide hinging and fastening means for a door which will give both strength and stability, and withstand the varying stresses due to changes of temperature.

My invention was especially suggested by the needs of a silo door, but may also be used to advantage in many other instances.

The construction, application and operation of my invention will be more readily understood by having reference in the first instance to the accompanying drawings, in which:

Figure 1 is a fragmental front elevation of a silo in which the doors are provided with hinging and fastening means invented by me; Fig. 2 is a horizontal section taken approximately on the line 2—2 of Fig. 1, through one of the silo doors; this figure showing the relative position of the operating parts when the door is closed; Fig. 3 is another view like Fig. 2, showing the position of the operating parts when the door has been released from its jamb; and Fig. 4 is a detail of construction.

The door jambs, *a*, of the silo are rigidly held spaced apart by spacing-bars, *b*, set transversely at the top and bottom of the door openings, and constituting the top and bottom of the door frame. These bars, *b*, are shown only in Figs. 2 and 3. Angle-irons, *c*, are bolted

to the jambs, *a*, and the spacing-bars *b*, said angle-irons constituting the sills and top of the door-frame; and the door jambs, *a*, being formed by the staves, *d*, of the body of the silo. Said staves are tongued and grooved together in the usual manner so as to give an air-tight fit when compressed together. Swivel lugs, *e*, are journaled between each pair of angle-irons, *c*, and have threaded into them the ends of adjustable tightening bands or hoops *f*. On the angle-irons *c* are pivoted at *c'* the hinge-brackets, *g*, supporting the top and the bottom of the door. Said hinge-brackets are each made with a gear segment *g'*, of which the pivotal point *c'* is the center. Said hinge-brackets are each further made with a hinge pintle *g*², and a perpendicularly projecting stop *g*³ (shown more clearly in Fig. 1) which limits the rotation of the hinge-brackets.

The doors *h* are made in the usual manner and are provided on the outside with cross braces *h'* on which are mounted ladder rungs *h*², as shown in Fig. 1. The doors are adapted to swing inside of the silo and when closed will overlap the edges of the door jambs (as shown in Figs. 2 and 3) and also the spacing bars *b*. Near the top and bottom portions of each door is fastened transversely a metal strap *i*, one end of which is made with a hinge-knuckle *i'* for the pintle *g*² of the hinge bracket *g*. The other end of the strap, *i*, is formed with a lock-lip *i*², as shown in Figs. 2 and 3. The doors *h* are arranged one above the other.

The operating mechanism for the doors consists of a vertical shaft *m* journaled at its ends in the angle-irons *c*, located at the bottom and the top of the door. Rigidly mounted on the end of the shaft *m* are pinions *m'* which mesh with the related gear-segments *g'* of the hinge brackets *g*. A handle *n* is fastened on the shaft *m* so as to render the partial rotation of the latter convenient, by which the door opening and fastening means are actuated. To each pinion *m'* is connected one end of a bar *o*, longitudinally movable in a bearing *p*, fastened on the related angle-iron *c*. The bars *o* serve the purpose of latch-bolts.

In explaining the operation of my improvement, let it be assumed that the door is closed as shown in Fig. 2. The handle *n* is seized and given a quarter turn, thereby

bringing it to its position in Fig. 3. Such action has withdrawn the latch-bolts, o , from their engagement with the lock-lips i^2 . The rotation of the shaft m has also 5 caused the pinions m' to so move the gear-segments g' as to position the hinge-brackets g as shown in Fig. 3; in so doing moving the door h inward from its jamb; and the door may then be swung to the left 10 (as shown in dotted outline in Fig. 3) so as to clear the door opening. When later the door is again to be shut, it will first be moved back to its position shown in full lines in Fig. 3. The handle n will then be 15 given a quarter turn to the left, thereby rotating the shaft m and therewith the pinions m' , which will move the gear segment g' outward; in so doing drawing the door against its jamb, and finally projecting the 20 extremities of the latch bolts, o , behind the lock-lips i^2 . The operated parts have now been restored to the position in which they are shown in Fig. 2, and the door will be secured in place at each of its four corners. 25 The detail Fig. 4 shows that the pinions m' are made with stub-axes m^2 , journaled in the angle plates c and held in place by means of keys m^3 . The pinions m' have square eyes extending only part way 30 through, in which square eyes are set the ends of the shaft m .

Fig. 4 also shows more clearly that the pinions m' are made with flanges m^4 for restraining the gear segments g' against movement in a vertical plane. The lower 35 of the hinge brackets g bears upon the door sill and the upper thereof against the top of the door casing. The construction shown effectively holds the hinge brackets against 40 rotation in a vertical plane, either longitudinally or transversely.

It will be noticed from Fig. 2 that when the door is closed and latched, as described, the ends of the latch bars, o , fastened to the pinions m' , are so located as to hold said pinions against reverse rotation while the opposite ends of said latch bars are forced wedge-like behind the lock-lip i^2 ; it being understood that the latch bars have 50 some spring.

I claim:

1. The combination with a door casing of a pair of hinge-brackets pivoted at the bottom and the top of the door casing, a door hinged at one side to said hinge brackets, 55 said hinge brackets formed with a gear segment; a revolute shaft; pinions fixed on the ends thereof and meshing with said gear segments of the hinge brackets; and a latch element for fastening the opposite side of the door, such latch element operatively connected to said pinions.

2. The combination with a door casing of 60 a pair of hinge brackets pivoted at the bottom and the top of the door casing, a door hinged

at one side to said hinge brackets, said hinge brackets formed with a gear segment; a revolute shaft; pinions fixed on the ends thereof and meshing with said gear segments of the hinge brackets; a lock-lip on 70 the opposite side of the door; and latch-bolts connected to said pinions adapted to be engaged with and disengaged from said lock-lips by the rotation of said pinions.

3. The combination with a door casing of 75 a pair of hinge brackets pivoted at the bottom and the top of the door casing, a door hinged at one side to said hinge brackets, 80 said hinge brackets formed with a gear segment; a revolute shaft; pinions fixed on the ends thereof and meshing with said gear segments of the hinge brackets; a handle for rotating the shaft; and a latch element 85 for fastening the opposite side of the door, such latch element operatively connected to 90 said pinions.

4. The combination with a door casing of 95 a pair of hinge brackets pivoted at the bottom and the top of the door casing, a door hinged at one side to said hinge brackets, 100 said hinge brackets formed with a gear segment; a revolute shaft; pinions fixed on the ends thereof and meshing with said gear segments of the hinge brackets; a handle for rotating the shaft; a lock-lip on the opposite 105 side of the door; and latch bolts connected to said pinions adapted to be engaged with and disengaged from said lock-lips by the 110 rotation of said pinions.

5. The combination with a door casing, of 115 a pair of hinge brackets pivoted at the bottom and the top of the door casing, a door hinged at one side on said hinged brackets, 120 means for latching the opposite side of the door, means for moving said hinge brackets in and out on their pivots to thereby move the door from and 125 on its seat, means included in said moving means for holding the hinge brackets against rotation in a vertical plane either longitudinally or transversely, and 130 connections between such hinge brackets moving means and said door latching means adapted to operate the latter concurrently with the former.

6. The combination with a door casing of 135 a pair of hinge brackets pivoted at the bottom and the top of the door casing, a door hinged at one side to said hinge brackets, 140 said hinge brackets formed with a gear segment; a revolute shaft; flanged pinions fixed on the ends thereof and meshing with said gear segments of the hinge brackets; and a latch element for fastening the opposite side of the door, such latch element 145 operatively connected to said pinions.

7. The combination with a door casing of 150 a pair of hinge brackets pivoted at the bottom and the top of the door casing, a door hinged at one side to said hinge brackets,

said hinge brackets formed with a gear segment; a revoluble shaft; flanged pinions fixed on the ends thereof and meshing with said gear segments of the hinge brackets; a lock-lip on the opposite side of the door; and latch-bolts connected to said pinions adapted to be engaged with and disengaged

from said lock-lips by the rotation of said pinions.

FREDOLIEN J. OBERER.
